UNITED STATES PATENT OFFICE.

NAPOLEON AUBIN, OF CANADA.

IMPROVEMENT IN WATER-METERS.

Specification forming part of Letters Patent No. 36,201, dated August 19, 1862.

To all whom it may concern:

Be it known that I, NAPOLEON AUBIN, a citizen of the United States, at present residing in Canada, have invented certain new and useful Improvements in Fluid-Meters; and I do hereby declare that the following, taken in connection with the drawings, is a full, clear, and exact description thereof.

In the drawings, Figure 1 is an elevation of the meter. Fig. 2 is a vertical section through the same. Fig. 3 is a plan of the valve-seat seen from the lower side; and Fig. 4 is a vertical section through the lost-motion contrivance in a plane perpendicular to the section, Fig. 2.

This meter has been devised with regard to cheapness of construction and efficiency and accuracy in operation. It contains some features identical with those described in an application made by me for a patent now pending, and it is intended more especially for a house-meter, or a meter through which comparatively small quantities of water are delivered. Its main features are a diaphragm, a short slide-valve, and a reversing apparatus, and there are to be found in it certain novelties in construction, and also a novel combination of mechanism.

The whole meter is inclosed in a case or receptacle made in four pieces, *a a b b c c d d*. The two former constitute the measuring-chamber of the meter, and also contain the tumbling-bob or reversing apparatus, and likewise constitute a side pipe. The piece *c c* contains the passages leading from the ports, and the piece *d d* forms the valve-chest. The valve-seat *e e* is a separate piece, merely dropped into place and formed separate so that it may be readily planed and ground or otherwise fitted for use, and also so that the valve-seat may be of a metal superior in durability and less liable to rust than other parts of the meter. I intend to make the valve-seat of brass and the case of iron or some soft alloy.

The parts *a a* and *b b* are joined to each other at the place of confinement of the diaphragm, and the diaphragm packs the joint between them. This diaphragm *e e* may be of india-rubber, leather, or other suitable material, and has bolted to it two plates, *f f*, and also a standard, *g g*, which may be either two staples, such as shown in the drawings, secured side by side with an interval between them,

or a hollow frustum of a cone, or a cylinder or box with a hole in the top.

Just above the utmost range of the diaphragm is secured a rock-shaft, *h*. It has two arms, *i j*. To the former is pivoted a rod, *k*, with a T-head, which lies in the conical frustum or between the staples. The latter, *j*, enters a fork on the lower end of a lever, *l*. This lever is pivoted near its center, and its upper end passes through one of the ports in the valve-seat and enters into a hole in the valve. A spring, *m*, bears upon a pin projecting from the arm *j*. This spring is secured at its upper end, and is so constructed—something like a sash-lock spring—that it tends to vibrate the lever whenever the arm *j* has passed the vertical in either direction. The spring is compressed by the rock-shaft when the arm *j* is forced to rise from either side toward the vertical, and when *j* has passed the vertical in either direction the spring expands and throws the rock-shaft over. The rock-shaft, arms, rod, spring, and lever I term the "reversing apparatus," and a weight may be used in place of the spring, and the apparatus may be variously modified, so long as a weight is raised or a spring compressed by the motions of the diaphragm, either up or down, and then by the falling of the weight or the expansion of the spring a valve is moved.

Upon the valve-seat slides a short slide-valve, *n*. This seat has in it, as usual, three ports, the center one leading to the exhaust-passage *o* and the other two one to each side of the diaphragm.

Water is to pass through the induction-pipe *p*, and will thence flow through the passage *q* and depress the diaphragm. Water beneath the diaphragm will flow out through *s* through one of the ports, through the valve-cup, and out through the exhaust-port *o*. When the diaphragm descends so low that the top of *q* strikes the T-head on *k*, the rock-shaft will commence to oscillate, compressing the spring. When its arm reaches the vertical, the spring will throw the rock-shaft over, and the lever will reverse the valve *n*, so that water will now enter through *s* and flow out through *q*, and the diaphragm will commence to rise and will keep rising. While so doing the upper plate on the diaphragm will strike the T-head, which will move the rock-shaft, and it will compress the spring until the latter throws the valve

over again into the position shown in the drawings. A rod and lever—such as xy —are to be attached to some moving part of the apparatus, and they are to give motions to some appropriate counter or register of strokes of the diaphragm.

In this meter the diaphragm that is moved by and regulates the influx of water is connected directly to the reversing apparatus without the interposition of a pressure-plate, as described in my other application for a patent now pending, and it will be observed that no stuffing-boxes are here employed in order to make connections between the diaphragm and the valve; also, that the valve-seat is a separate piece dropped into place, and that the side pipe is cast or formed in both ports of the case, the joint in it being packed by a part of the diaphragm, which has a hole cut through it. I intend to pivot the lever and rock-shaft in a frame, which also supports the upper end of the spring, and slip this frame into place, holding it by screws, solder, pins, or otherwise, and also at times to cast the piece c in one with the piece b .

In this meter, also, the valve is of such length that it will not cover both ports at the same time, and this peculiarity I find to be advantageous in practice, as the valve is more easily moved from one side to the other when the meter is used under a considerable head of water. This construction, of course, involves some leakage which is not measured; but that leakage is nearly the same at each

stroke, and can be allowed for and added to the quantity of water indicated by the register as having passed through the meter.

I sometimes intend to use a valve with lap, as in ordinary short slide steam-valves.

I claim as of my own invention—

1. The combination of a diaphragm with a reversing apparatus and a short slide-valve connected each with the other without the use of stuffing-boxes, and the whole inclosed within a proper receptacle containing a valve-seat and constituting a fluid-meter, substantially such as is described, and acting substantially specified.

2. A receptacle constructed in two pieces, one half of which contains part of the side pipe and the other half the other part thereof, when the joint between the two is made by a diaphragm, and the latter acts on a reversing apparatus contained in one half of the said receptacle, the construction being substantially such as described.

3. In combination with a diaphragm of a water-meter, a short slide-valve of less length than the distance from the outside of one port to the inside of the other port, the combination being substantially such as described.

In testimony whereof I have hereunto subscribed my name.

N. AUBIN.
